UNITED STATES PATENT OFFICE.

OLIVER N. MAY, OF WINDSOR, NEW YORK.

MACHINE FOR PLANING OR DRESSING SAWED SHINGLES.

Specification of Letters Patent No. 1,138, dated April 29, 1839.

To all whom it may concern:

Be it known that I, OLIVER N. MAY, of 5
Windsor, in the county of Broome and State
of New York, have invented a new and use-
ful Improvement in Machines for Planing
or Dressing Sawed Shingles, and that the
following is a full and exact description
thereof, reference being had to the drawings
accompanying and making part of this speci-
10
fication, in which the same parts are desig-
nated by the same letters of reference in all
the different figures.

Figure 1 represents a perspective view of
15
the machine in which both ends of the car-
riage are used for planing shingles. Fig. 2
a longitudinal section of Fig. 1, through the
carriage and other parts of the machine;
Fig. 3, a section view of a machine in which
20
only one end of the carriage is used for plan-
ing shingles. Fig. 4, exhibits the position of
the grooves on the inside of the frame, and
Fig. 5 a perspective view of a part of the
inside of the frame and carriage, exhib-
25
iting the bar within the upper groove.

30
The sides of the frame *a*, Figs. 1, 2, 3, 4
and 5, is formed of two longitudinal pieces
of timber, about ten feet in length, three
inches thick, and eight wide, framed to-
gether by two or more transverse timbers *a'*,
35
about one foot long within the sides of the
frame *a*, Figs. 1, 2 and 3. The longitudinal
timbers *a*, rest and are connected to posts
or frames *a''*, Fig. 1, which are of the re-
quisite length to give the desired height to
40
the machine. On the inside of the pieces *a*,
Figs. 1, 2, 3, 4 and 5, about two inches below
the top is formed a groove *b*, of sufficient
length and size to receive the flanges of the
carriage *c*. This carriage is about four feet
45
long, with flanges projecting laterally from
its lower edges which move in the before
mentioned grooves *b*, parallel with the top
of the frame. The carriage at the center or
middle distance between the two ends, is
50
about four inches thick, and about three at
the ends, the upper surface slanting down-
ward toward the ends, at an angle in accord-
ance with the taper of the shingle, that when
a shingle is placed upon the carriage, with
55
its point toward the center, its upper sur-
face is parallel with the sides *a*, in which the
carriage *c*, moves, and the cutting instru-
ment operates uniformly upon the upper
surface of the shingle.

55
The carriage *c*, is put in motion by a

double crank *d*, placed near one end of the
machine, with a crank at each side of the
frame, the axle of which extends through
the frame, and its journals move in boxes
secured within the side pieces *a*, on a line 60
with the grooves *b*, Figs. 1, 2 and 3. Within
the frame, there is attached to the axle of the
cranks, a gear wheel or pulley *e*, to which the
motive power is applied. Pitmen or shackle
bars *h* are attached to each of the cranks *d*, 65
and extend to the opposite end of the car-
riage *c* and are connected to it by projecting
studs *f*, secured to the carriage and passing
through the side pieces *a*, at the grooves *b*,
70
by being formed into slots or mortices *g*, in
length sufficient for the cranks *d*, to propel
the carriage *c*, the requisite distance for
planing the shingles, as shown at Fig. 1.
Transversely at the center of the carriage *c* 75
a groove is formed, in which a metallic
bar *i* is inserted for propelling the shingles.
This bar is about one inch longer than the
groove in which it is placed, the ends of
which move in parallel grooves *k*, formed
above the grooves *b*, in which the carriage 80
move. The grooves *k*, raise the bar *i*, suffi-
ciently above the carriage to which it is
attached, to force the shingles beneath the
plane stock *o*, which performs the planing
operation, and the projection *j*, or interme- 85
diate piece between the grooves *k* and *b*, ter-
minates and the two grooves are united at
such a position with the machine that when
the bar *i* has arrived at the plane stock and
comes in contact with the projection on the 90
under side of the plane stock this interme-
diate piece *j* here terminates and the two
grooves are here united, and the bar *i* de-
scends beneath the projection, and brings
the shingle without the planing instrument. 95

When both ends of the carriage *c*, and
both plane stocks *o* are used, the bar *i*, re-
turns in the same groove *k*, in which it
moved in the last operation, but when only
one end of the carriage *c* is used the bar *i*, 100
instead of returning in the upper groove *k*,
is caused to descend to the lower groove *b*
by the action of the spring *l*, Figs. 1, 2, and
3, which is brought down by the hand or the
application of a weight. The bar *i*, is about
one inch square and secured in the carriage,
by projecting arms, that extend downward
at right angles and are firmly secured to the
under side of the bar *i*, and the bar *i* is sus- 105
ceptible of a vertical movement and is forced 110

up by the springs *s*, as shown at Fig. 2. The principal object of the springs *l*, which are applied to one or both ends of the machine, is to stop the operation of the machine, in case of misplacing of the shingles, or by the bar *i* slipping from the point of a shingle, by which the bar *i* is brought to operate against the butt of the shingle, in such case by depressing the bar *i* by the spring *l* and 10 commence the operation at the opposite end the operation is again correct.

At the under side and at each end of the plane stocks, within the side pieces *a*, and directly above the groove *k*, are formed 15 projections, *t*, that extend down a sufficient distance to depress the bar *i*, that in passing under the plane stock, it will not come in contact with the cutting instrument connected thereto as shown at Fig. 8. Beneath 20 the timbers *a*, are placed the springs *q* to which are attached a rod or bolt *p*, that extends upward through the side pieces *a*, and are firmly secured to the ends of the plane stocks *o*, and guide them in a vertical direction, if they are raised from their seat, by a 25 shingle passing beneath them, that is thicker than the plane stock will admit in its lower position, and is forced down with a sufficient degree of pressure to perform the operation 30 of planing by the action of the springs *q*, Figs. 1, 2 and 3.

At each side of the bar *i* a transverse groove is formed in the carriage in length a little more than half the width of the carriage, in which is placed a movable bar *u*, connected to the short end of a lever *r*, placed beneath the carriage by a projection extending downward from the under side of the bar *u*, to which it is secured. In the 40 operation of the machine, when the shingles are removed from the hopper *n*, (in which they are placed previous to the operation of planing), by the bar *i*, and remain upon the carriage without the plane stock, they are 45 prevented from returning by the action of the bar *u*, by raising the tip of the shingle so that it strikes against the back of the plane-stock, and as the carriage returns, the shingles fall off at the end of the carriage. The levers *r* are so arranged that when the bars *u* are without and advancing toward the plane-stock, they are made to 50 assume a level with the carriage before they arrive at the plane-stock, by the long end of 55 the lever coming in contact with a piece of timber extending across the frame, at the lower edge of the timbers *a*, Fig. 2, which raises the long arm of the lever, and depressing the short arm and the bar *u*, to 60 which it is connected as seen at Fig. 2, and remains in that position, while the bar *u* is within the plane-stock, but as soon as the bar *u* passes out beneath the plane-stock, the long end of the lever *r*, passes off the trans- 65 verse timber and pulls by its gravity, and

raises the tip of the shingle as soon as it leaves the plane stock.

Fig. 3 represents a sectional view of a single machine in which only one end of the carriage is used and one plane-stock for 70 planing shingles. The end of the carriage that supports and moves the shingle is made tapering, inclining downward from the bar *i*, to the end; the bar *i*, is raised a sufficient height to take hold of the tip of the shingle, 75 and the opposite end of the carriage is parallel with the frame *a*, and even with the top of the bar *i*, as seen at Fig. 3. In this machine the spring *l*, and groove *k*, are dispensed with, and the bar *i*, in passing under 80 the plane-stock *o*, strikes the projection *t*, and raises the plane-stock, sufficient for the bar to pass the cutting instruments, without coming in contact with the edge as represented at Fig. 3. The bar *i*, is secured to 85 the carriage in any applicable manner. Upon the upper edge of the timber *d*, are secured two stands, that support the axis of the comb *v*, that extends across the frame, with a row of projecting teeth inserted at 90 the lower edge as seen at Figs. 3 and 7.

Fig. 6 is a longitudinal section of a machine, with a planing instrument *o'* secured to the carriage near the outer end, which carriage is similar to the one described in 95 Fig. 3, with only one end that is used for planing shingles. As the shingles are brought out from the plane-stock *o*, by the bar *i*, it brings the tip of the shingle within the catch *w*, attached to the end of the timber *x*, and the shingles are prevented from returning by the points at the under side of the lever or dog *y*. When the carriage has commenced its retrograde movement and the bar *i*, is brought from under the catch *w*, 100 the timber *x*, and catch *n*, are forced down by the action of the weights *z*, the catch *w*, preventing the shingle from moving back, and the timber *x*, confining the shingle to 105 the surface of the carriage, while the cutting instrument *o'*, at the end of the carriage, planes the under surface of the shingle, while the carriage is returning, thus completing the operation, by planing the 110 upper surface of the shingle when it is removed from the hopper *n*, beneath the plane-stock *o* and planing the under side when the carriage returns.

The plane-stock is formed of metal, in the ordinary form, and the planing instrument secured therein by screws and wedges, and the projections *t*, before described may be attached to the upper surface of the bar *i*, instead of the plane-stock.

The invention claimed, and desired to be secured by Letters Patent, is—

1. The carriage *c*, inclining downwardly from the middle, toward one or both ends, at an angle of about two degrees in accordance with the taper of the shingle, in combina- 130

tion with the movable, or stationary bar *i*, that propells the shingle, all being constructed substantially as herein before described.

5 2. I also claim the projection *t*, secured to the under side of the plane-stock *o*, that depresses the movable, and is raised by the

stationary bar *i*, as herein set forth and described.

OLIVER N. MAY.
